SIGNORS TO DRAPER CORPORATION, OF HOPEDALE, MASSACHUSETTS, A CORPORA-
TION OF MAINE.

FILLING-CONTROL MECHANISM FOR FILLING REPLENISHING LOOMS.

Application filed September 17, 1926. Serial No. 136,101.

This invention relates to filling replenishing looms whereby the filling in the shuttle is changed from time to time while the loom continues to run, and is more particularly directed to the mechanism for controlling the filling and filling carriers.

In filling replenishing looms of this general type, the filling carriers are mounted in a hopper and are successively moved to transferring position following each replenishing operation. During the replenishing operation the substantially exhausted filling carrier in the shuttle is ejected and the end of the filling leading therefrom extends to the cloth selvage. Should the filling replenishing mechanism fail to effect a transfer of filling to the shuttle, it may happen at times that the filling leading from the substantially exhausted filling carrier may be parted by the thread parting mechanism, notwithstanding no transfer has been effected, and under these conditions one or more picks will fail to lay filling in the shed.

It has heretofore been proposed to provide means for preventing the action of the thread parting mechanism should filling replenishment not be effected, and such means has sometimes been associated with the transferring mechanism, so that if the transfer fails to operate, the thread parting mechanism will be rendered inactive.

It has also been proposed heretofore to provide a yielding support to engage the under portion of the head of a filling carrier in the hopper when in transferring position and to effect movement of such guiding support by the passage of the filling carrier from the hopper to the shuttle.

The present invention contemplates the provision of mechanism for supporting a filling carrier in the hopper when in transferring position and to effect movement of said support from its supporting position by movement of the filling carrier from the hopper. Advantage is taken of this movement of the filling carrier support to cause operation of the thread parting mechanism, so that should a carrier not be transferred to the shuttle on call for replenishment, the thread parter will not operate.

The invention and new combination of parts will best be made clear from the fol-

lowing description and the accompanying drawings of one good form thereof wherein the guiding support for the filling carrier in transferring position is associated with an independent train of mechanism for controlling the operation of the thread parting mechanism, as will more fully appear.

In the drawings:

Fig. 1 is a perspective view of a loom at the filling replenishing side thereof, containing the present invention;

Fig. 2 is a sectional elevation through the inside of the hopper looking to the left, Fig. 1;

Fig. 3 is a section on the line 3—3 of Fig. 2; and

Fig. 4 is an enlarged detail showing the thread parter and the actuating member therefor.

In the present instance of the invention, the hopper for the filling carrier is shown as of the rotary type wherein after each transfer of a filling carrier to the shuttle, means are set in actuation for moving the rotary hopper to bring the next filling carrier in position for transfer, but as such mechanism for rotating the hopper does not form a part of the present invention, any appropriate means may be employed.

The loom frame 1 is of usual construction, and mounted upon the front portion of the loom is the hopper stand 2 which may be suitably supported from the breast beam of the loom by a base plate 3. Mounted for rotary movement on the hopper stand is the filling carrier 4 which is shown as mounted upon a stud 5 secured to the hopper stand. The hopper stand is provided with a laterally extending stud 6 on which is mounted the transerrer 7 having a downwardly extending arm 8 pivotally connected at 9 with a dog 10 which on call for replenishment of filling is raised into the path of a hunter 11 carried by the lay 12, the effect being that upon call for replenishment of filling through any well-known form of detecting mechanism, the transerrer will be actuated to transfer a filling carrier from the hopper to the shuttle 13 beneath, which is provided with a bottom opening 14 for the passage of the ejected filling carrier. This mechanism may be of usual construction, and associated therewith is the shuttle feeler

15 which on call for replenishment of filling is moved rearwardly, as usual in this type of loom, to detect whether or not the shuttle 13 is properly boxed.

5 The hopper stand 2 has a flange portion 16 which surrounds the rotary hopper adjacent the heads of the filling carriers 17 and is provided near the lower portion thereof with an opening 18, as indicated in Fig. 2.

10 Mounted upon the loom frame is an abutment or stop 19 against which rests the filling carrier when in transferring position.

Pivotedly mounted upon the hopper stand 2 at 20 is a swinging arm 21 which extends 15 downwardly from its pivotal support and at its lower end is provided with a guiding support 22 for the filling carriers, the front edge portion of which is inclined or bevelled, as at 23, so that upon movement of a filling 20 carrier from the hopper on replenishment, the support 22 will be moved rearwardly to thereby swing the swinging arm 21 rearwardly. The support 22 for the filling carrier in transferring position has a rearwardly 25 extending tail portion 24 which underlies the filling carrier next to be moved to transferring position, as indicated in Fig. 2, and the top surface 25 of the tail portion 24 is eccentric to the arc of movement of the 30 rotary hopper, with the result that should a filling carrier next to be moved to transferring position be displaced in the rotary hopper, the surface 25 of the tail 24 will act upon the head portion of such filling 35 carrier and move it upwardly to its full supporting position in the hopper. As will be noted in Fig. 2, the junction between the inclined portion 23 and the surface 25 of the filling carrier and guiding support bears 40 against the head of the filling carrier when in transferring position at a point back of the path of movement of such filling carrier as it is transferred, with the result that the inclined portion 23 will cause the arm 21 to swing rearwardly as the filling carrier 45 is transferred.

It is important that the guiding support for the filling carrier in transferring position may be properly related to such filling 50 carrier, and as the head portions of the filling carriers may sometimes vary in size or in accordance with the character of the filling carrier employed, means are herein provided for adjusting the operative position of the 55 swinging arm 21 and consequently the guiding support for the filling carrier. The swinging arm 21 is normally under the influence of a spring 26, one end of which is connected to the swinging arm at 27 and 60 the other end to a pin 28 extending from the hopper stand, and projecting from the hopper stand is a lug carrying an adjustable stop. The adjustable stop may be variously contrived, but in the present instance it 65 is shown as an adjusting screw 30 which is

threaded into the lug 29 and is provided with a locking nut 31, the result being that the swinging arm and perforce the guiding support for the filling carriers may be accurately placed in operative position to conform to the varying characters of the filling carriers employed.

In accordance with one feature of the present invention, the filling carrier guiding support is associated with means independent 75 thereof for causing the thread parting mechanism to part the thread of the outgoing filling carriers only when the filling carrier support and swinging arm 21 are moved rearwardly by the passage of a filling 80 carrier from the hopper to the shuttle.

This independent train of mechanism may be variously contrived, but in the present instance consists of a stud or support 32 extending from the hopper stand, and mounted 85 for rocking movement on the stud 32 is the rocker 33, the upwardly extending arm 34 of which is under the influence of a pull spring 35 connected to the swinging arm 21, the result being that on rearward movement of the swinging arm due to the passage 90 of a filling carrier from the hopper to the shuttle, the rocker 33 will be actuated.

The pull spring 35 may be varied in construction and connection with regard to the 95 swinging arm 21, but in the present instance the end portions of the spring 35 are connected to lugs 36 and 37, the former of which is mounted on a pin 38 extending from the arm 34 of the rocker, and the lug 37 is connected to a pin 39 extending from the arm 40 adjustably connected to the lower end portion of the swinging arm 21, as indicated at 41, the construction being such that should the swinging arm be moved rearwardly by 105 the passage of a filling carrier from the hopper at transferring position, the pull spring 35 will yieldingly act upon the rocker 33 and cause rocking movement thereof, and on the return of the swinging arm to normal 110 position again, the compression of the spring will move the rocker to its initial position.

The shuttle feeler 15 is provided with a thread parter which is best shown in detail in Fig. 4, and if desired, the thread parter 115 may be associated with a thread clamp, as usual in shuttle feeler thread parters and clamps.

The thread parter comprises the movable parting member or cutter 42 which is pivotally mounted on the stud 43 extending from the shuttle feeler. Associated with the movable thread parter is the fixed thread parter 44, so that upon actuation of the movable thread parter, the filling thread *a* which will 120 then be in position, as indicated in Fig. 4, will be parted or cut. If desired, the thread parter may have associated therewith the thread clamping members 45 and 46, but as such parts are not essential to the inven- 125 130

tion they may be of usual construction now well-known in the art.

The movable parting member 42 is provided with an upper cam surface 47 which is engaged by a parter actuator 48 having an end portion 49 overlying the cam surface 47. The parter actuator 48 is secured to the rocker 33 at 50, and in the present instance of the invention is shown as secured to the rocker by means of a screw bolt 51, so that the actuator may be adjustable with respect to the rocker to properly act upon the parting member of the thread parter.

From the construction described it will be obvious that on call for replenishment of filling, the transferer will move the filling carrier then in transferring position from the hopper to the shuttle, and during such movement the guiding support 22 and the swinging arm 21 will be moved rearwardly. Simultaneously with the call for replenishment of filling, the shuttle feeler 15 is moved rearwardly to shuttle feeling position, the guiding support 22 and swinging arm 21 are moved rearwardly as described during replenishment, and the rocker 33 will be yieldingly rocked under the action of the spring connection to move the thread parting actuator 48 downwardly and cause the end 49 thereof to act upon the cam surface 47 of the parter to thereby part the thread leading to the outgoing filling carrier.

Where a thread clamp is employed in connection with the parter, it is usual to maintain the end of the filling leading to the cloth selvage under control of the clamp, a condition which is indicated in Fig. 1, and on rearward movement of the feeler, means are provided to open the thread parter 40 and clamp, such means being a trip 51 mounted upon an arm 52, as usual, and acting upon a pin 53 extending from the thread parter and clamp. After replenishment has been effected and the outgoing filling thread 45 parted, the hopper will be moved to bring the next filling carrier in position for transfer, and during such movement the surface 25 of the filling carrier guiding support 22 will bear upon the head of the filling carrier as it moves to transferring position and force it into its proper operative position in the hopper.

What is claimed is:

1. In a filling replenishing loom, the combination of a hopper and a hopper stand, a spring actuated swinging arm mounted on the hopper stand and provided with a guiding support for the filling carrier to be transferred, an adjustable stop for varying the operative position of the guiding support, an independent rocker mounted for rocking movement frontward of the guiding support, a thread parter for parting the filling of the outgoing carrier, a thread parter actuator 60 extending rearwardly from the independent

rocker, and a spring connection between the swinging arm and rocker for operating the parter only on displacement of the swinging arm during transfer.

2. In a filling replenishing loom, the combination of a hopper and hopper stand, a swinging arm pivotally mounted on the hopper stand and having a filling carrier support at its lower end which is displaced rearwardly by the passage of a filling carrier 70 during transfer into a position below the next filling carrier in the hopper, a spring acting on the swinging arm, a stop movable into different positions for varying the operative position of the swinging arm and 80 filling carrier support in response to the action of said spring, a shuttle feeler thread parter, a parter actuator independent of the carrier support and mounted in front thereof, and a spring connecting the swinging 85 arm and actuator.

3. In a filling replenishing loom, the combination of a hopper, a guiding support for the filling carrier to be transferred, a thread parter for parting the filling of the outgoing filling carrier, a rocker mounted independent 90 of the guiding support and having a thread parter closing member, and a pull spring connection between the guiding support and independent rocker for operating the thread 95 parter only in case a filling carrier is transferred.

4. In a filling replenishing loom, the combination of a hopper, a guiding support for the filling carrier to be transferred which 100 is displaced by the filling carrier during transfer, a thread parter for parting the filling of the outgoing carrier, a rocker bearing frontward of the guiding support, a rocker independently mounted on the rocker 105 bearing and having a thread parter closing arm extending rearwardly therefrom, and a spring extending frontwardly from the guiding support and connected to the independently mounted rocker for operating the 110 thread parter when a filling carrier is transferred.

5. In a filling replenishing loom, the combination of the hopper and hopper stand, a swinging arm having a filling carrier support provided with an inclined or bevelled front portion for rearward displacement of the swinging arm by the passage of a filling carrier, a shuttle feeler thread parter, a 115 rocker and rocker support mounted on the loom in front of the swinging arm, a pull spring connecting the swinging arm and rocker, and a thread parter actuator extending rearwardly from the rocker for operating the parter.

6. In a filling replenishing loom, the combination of the hopper and hopper stand, a swinging arm having a filling carrier support provided with an inclined or bevelled front portion for rearward displacement of 120 125 130

the swinging arm by the passage of a filling carrier, means for varying the operative position of the filling carrier support, a shuttle feeler thread parter, a rocker and rocker support mounted on the loom in front of the swinging arm, a pull spring connecting the swinging arm and rocker, and a thread

parter actuator extending rearwardly from the rocker for operating the parter.

In testimony whereof, we have signed our 10 names to this specification.

EDWARD C. BURNHAM.
HARRY A. DAVIS.
